OIL BURNING EQUIPMENT

George P. Haynes, Brooklyn, N. Y., assignor to
 Todd Combustion Equipment, Inc., New York,
 N. Y., a corporation of New York

Application July 3, 1936, Serial No. 88,736

2 Claims. (Cl. 158—1)

This invention relates to oil burning equipment and my improvements, while not so limited, are intended particularly for use on marine vessels.

As will presently appear I propose to provide 5 an air tight and water tight bulkhead or partition extended transversely across the fire room in front of and suitably spaced from the boilers, to thus separate the main portion of the fire room from the boilers and their furnaces, said fire 10 room being divided into a boiler compartment and an operator's compartment.

The burner equipment, which is connected through the air register with the boiler front plate, penetrates the bulkhead and is connected 15 with said bulkhead by means of an expansible bellows, to absorb expansion and other distortions which occur between the boiler and bulkhead.

Other features and advantages of my invention will hereinafter appear.

20 In the drawings:—

Figure 1 is a sectional elevation of my improved oil burning equipment, taken on the line 1—1 of Fig. 2, and including the burner, air tight partition that is penetrated by said burner, air register, and expansible bellows connection between the partition and register.

Fig. 2 is a front elevation showing a bulkhead in a fire room with the burner portions projecting forwardly thereof.

30 Dealing in the first instance with the compartmented fire room wherein the boilers are shut off from that portion of the fire room occupied by the furnace attendants, let 1 indicate a bulkhead which extends transversely across the fire 35 room and serves as an air and water tight partition to separate a boiler compartment A from the fire room compartment B that is adapted for human occupancy at atmospheric pressure; it being intended to supply air under pressure, by 40 any suitable means, into compartment A for combustion purposes.

The air register is shown as provided with a pressed steel frame having divided members 2 that are bowed and engage by studs 3 with a ring 4 that is secured to the boiler front plate 5, said ring also carrying the usual Venturi ring 6.

The frame members 2 merge forwardly in a disk 7 that is provided with guide slots 8 for pins 9 that project from curved vanes 10 which are 50 housed within frame members 2, said vanes, near their rearward ends, having lugs 11 by which they pivotally engage the studs 3.

Also a rotatable plate 12 is provided, it too having slots 13, which engage pins 9 for the 55 rotation of the vanes.

The plate 12 carries a toothed sector 14 with which a pinion 15 is in mesh, said pinion having an operating shaft 16, with handle 17 for its manipulation.

A burner tube 18, with the usual atomizer 19 and flame cone 20 entered within the register, has the jacket 21 and is provided at its forward end with a usual form of oil supply means.

The burner tube, in its jacket, is entered through a hollow casting 22, in which it is 10 rendered air tight by a stuffing box 23, for a purpose to be described hereinafter. Also said casting is provided with a passageway for the reception of the shaft 16, and here too a stuffing box 24, is employed to render the fit air tight between shaft 16 and its passageway.

A radial web 25 extends from and surrounds the casting 22, in compartment A, intermediate bulkhead 1 and boiler plate 5 and in suitable spaced relation from the bulkhead, and an expansion bellows 26 is fitted between said web 25 and the bulkhead, said bellows at its rear end having a flange 27 that is clamped between web 25 and a ring 28 as with bolts 29; and said bellows, at its forward end having a flange 30 that 25 is clamped between bulkhead 1 and a ring 31 as with bolts 32.

As has been premised the expansion bellows is intended for the purpose of absorbing expansion and other distortions occurring between the bulkhead and boiler.

Thus, by means of the tight joints effected between the bellows, the web 25 and the bulkhead, as well as the stuffing boxes 23, 24, pressure of air in compartment A is precluded from entering compartment B, while the control means for oil supply to the burner and the operating handle for shaft 16 are projected into compartment B and therefore available to an operator therein.

It will be noted that the frame disk 7 is apertured for the reception of the casting reduced portion 33, and the rotatable plate 12, which is also apertured, has its bearing about a shoulder 34 upon said casting.

Plate 12, which is provided with a cover 35, is rotated by pinion 15 as meshed with sector 14, by the operation of shaft 16, and in such rotation the vanes 10, through the engagement of their pins 9 with the angled slots 13, are turned either inwardly to the closed position or outwardly to the open position, the angled slots 8 in fixed disk 7 serving to guide these movements.

A cover plate 36 is shown as carried by bulk-

head 1 and having the observation doors 37 and lighting door 38.

Variations within the spirit and scope of my invention are equally comprehended by the foregoing disclosure.

I claim:—

1. The combination with a boiler furnace having a front plate, a bulkhead in spaced relation to said plate to define a compartment therebetween, said bulkhead having an opening therethrough, a burner tube projected through the opening in said bulkhead into said compartment, a casting in which said burner tube is mounted, substantially rigid means connecting said casting to said plate and expansion bellows connecting said casting to the bulkhead about the opening therein and serving to permit relative movement between the front plate and the bulkhead.

2. The combination with a boiler furnace having a front plate, a bulkhead in spaced relation to said plate to define a compartment therebetween, said bulkhead having an opening therethrough, a burner tube projected through the opening in said bulkhead into said compartment, a casting in which said burner tube is mounted, substantially rigid means connecting said casting to said plate, a radial web on said casting, and expansion bellows having one end affixed to said bulkhead and its other end secured to said web, the arrangement being such so as to compensate for relative movement between the front plate and the bulkhead.

15

GEORGE P. HAYNES.
